CLAIM

The ornamental design for a load beam for press pack clamp, as shown.

DESCRIPTION

FIG. 1 is a top perspective view of a load beam for press pack clamp showing my new design;

FIG. 2 is a front elevational view thereof, the rear elevational view is a mirror image of FIG. 2;

FIG. 3 is a left side elevation view thereof, the right side elevation view is a mirror image of FIG. 3;

FIG. 4 is a top plan view thereof;

FIG. 5 is a bottom plan view thereof;

FIG. 6 is a cross sectional view taken along line 6-6 of FIG. 4; and,

FIG. 7 is an enlarged view taken from circle 7 of FIG. 6.

1 Claim, 4 Drawing Sheets
